UNITED STATES PATENT OFFICE.

ERNEST O. CARTWRIGHT, OF SPRINGFIELD, OHIO, ASSIGNOR TO CHARLES F. GARDNER,
OF SPRINGFIELD, OHIO.

GRAPPLE.

1,322,537.

Specification of Letters Patent. Patented Nov. 25, 1919.

Application filed March 28, 1919. Serial No. 285,846.

To all whom it may concern:

Be it known that I, ERNEST O. CARTWRIGHT, a citizen of the United States, residing at Springfield, in the county of Clark 5 and State of Ohio, have invented certain new and useful Improvements in Grapples, of which the following is a specification.

My invention has for its object to provide a grapple which is especially useful 10 in removing refuse from sewers, sumps and catch basins and depositing the same in a tank wagon or other conveyance for removal to a suitable dump.

It frequently occurs that refuse of various kinds, such as bottles, parts of metal 15 frames, rods, pieces of wood, tubing or other waste material find their way into sewers, catch basins and sumps. It is difficult to remove such articles from deep catch basins 20 with the ordinary fork or scoop now in common use and it is therefore one of the objects of the present invention to provide a grapple fork device which will grasp the articles regardless of their shape and which 25 has provisions whereby the grapple fork proper may be "locked" or held in its grasping condition while the refuse is being lifted out of the catch basin and placed over the collection tank wagon into which it 30 can be readily released by the user.

Generally speaking, the device comprises a handle or pole, on one end of which is fixed a fork, and to that fork a second fork is pivoted, the second fork being provided 35 with a lever portion to which is connected an operating rod that runs along parallel and in close juxtaposition to the handle to near its upper or outer end at which place there is provided a toggle lever device 40 that is connected with the handle and rod in such manner that by manipulating the lever device, the grapple fork may be opened and closed and when closed may be locked in the closed position to hold the contents while 45 the operator is lifting the same out of the catch basin and depositing the same in the collection wagon or tank without it being necessary for the operator to hold the rod from movement during the time he is raising 50 the material out of the catch basin for deposit in the receptacle.

The invention further includes those novel features of construction and arrangement of parts which will be first fully described and

then be specifically pointed out in the claims 55 and illustrated in the accompanying drawing, in which:

Figure 1 is a front elevation of the implement.

Fig. 2 is a side elevation of the same. 60

Fig. 3 is an enlarged detail perspective view of the toggle grapple lever.

In the drawing, in which like numerals of reference indicate like parts in all of the figures, 1 is the handle which is made of a 65 suitable length and to which the fixed fork 2 is secured by having its tine 3 fitted into the end of the handle, the handle being protected at this place by the usual ferrule 4. The fork 2 preferably has its tines curved 70 to one side as at 5 and the pivoted fork 6 is similarly curved at 9 in the opposite direction, the fork 6 having its fingers designed to lie between the fingers of the fork 2 when the parts are positioned as 75 shown in Fig. 2 of the drawing. The fork 6 has a lever portion 8 which is pivoted at 7 to the fork 2. The fork 6 is operated from adjacent the opposite end of the handle 1 by a device consisting of a rod 10 which 80 connects to the lever 8 and extends along the handle to near the opposite end of the same, at which place the rod 10 is connected to the end 15 of a handle 13, the handle 13 having an eye portion 14 to fit over the lugs 85 12 of the bracket 11 and is connected with the bracket by a link 17 that is pivoted at 18 to the catch lever 13 and at 19 to the lugs 12, the lever 13 being slotted at 16 to receive the link 17. The arrangement is 90 such that when the lever 13 lies as shown in Fig. 2, the center 18 is closer to the handle than the center 19 and hence any pull on the rod 10 serves to hold the lever 13 tighter 95 against the handle and thus locks, as it were, the fork 6 in fixed relation to the fork 2 so as to hold the matter grasped between the forks without the necessity of the operator holding the lever 13 while he is manipulating the load. 100

When the lever 13 is moved away from the handle, the fork 6 can be rocked on its pivot to open the same, thus positioning the forks 2 and 6 to enable them to grasp a load of material.

From the foregoing description taken in connection with the accompanying drawings, it is thought the complete construction,

operation and advantages of the device will be clear to those skilled in the art. The device, as before stated, is especially advantageous in clearing out deep catch basins as the handle can be made of almost any length desired and, due to the fact that the load in the fork can be locked by virtue of the construction of the lever 13 and its co-operative connections, the operator can manipulate the device in the same manner as if there were a simple rod-like handle provided as he does not have to hold the lever 13 in place.

What I claim is:—

- 15 1. A grapple comprising a handle, a fork fixed in one end of the handle, a second fork coöperating with the first fork and pivoted thereto, a rod for operating said pivoted fork that extends along the handle, and a
- 20 toggle lever device mounted on the handle

and connected with the rod adjacent to the end of the handle which is opposite the fork.

2. A grapple comprising a handle, a fork fixed to one end of said handle, a second fork coöperating with the first fork and pivoted thereto, a rod for operating said pivoted fork, a collar on the handle adjacent to the end farthest from the fork, a handle member connected with the rod and including a yoke portion, said collar having lugs adapted to project through said yoke portion, and a link connection between said lugs and said handle member, all being arranged whereby when said handle member lies against said handle the point of connection of said link with said lugs will lie in a different plane than that containing said yoke portion to thereby "lock" the parts substantially as shown and described.

ERNEST O. CARTWRIGHT.
